VOLUME CONTROL SYSTEM FOR AMPLIFIERS

George L. Beers, Merchantville, N. J., assignor
to Westinghouse Electric & Manufacturing
Company, a corporation of Pennsylvania

Application May 1, 1930, Serial No. 448,863

6 Claims. (Cl. 250—20)

My invention relates to receiving apparatus, more particularly to automatic volume control for a receiving set constituting an improvement over the system embodied in a prior application of mine, Serial No. 212,791, filed August 13, 1927, Patent No. 1,960,723, May 29, 1934.

In the above referred-to application, means are disclosed whereby a uniform desired sound level may be maintained during periods of reception. This desirable result is obtained by the provision of a control tube having a plate-circuit resistor which is connected in the grid circuits of a plurality of amplifier tubes of a radio receiving set, the positive end of the resistor being connected to the cathode and the negative end to the grid of the amplifier tubes. The grid of the control tube is connected to the grid of one of the tubes of the set in such manner as to receive signal impulses, with the result that the plate current of the control tube will fluctuate accordingly. An increase in signal strength, which would ordinarily increase the volume output of the loud speaker and possible overload certain of the tubes, will create a greater potential drop across the resistor in the plate-circuit of the control tube. This, in turn, will increase the negative bias on the amplifying tubes and so cut down the signal strength to the desired level. This action occurs simultaneously with the incoming signal, with the result that the sound level, when once set, is maintained substantially uniform, thereby correcting such undesirable occurrences as fading, or the sudden booming which occurs when switching from a comparatively weak station to a strong one.

The above described system functions very efficiently in serving its purpose of maintaining substantially uniform sound levels during reception periods. It has been found, however, that, during unusual circumstances, signals received tended to become distorted. These unusual circumstances occurred at intervals when very strong signals were received. The distortion of signals during those intervals of strong-signal reception is apparently due to applying a big grid swing to the grid of an amplifying tube which is biased just beyond the cut-off point, under which conditions, only the peaks of the incoming signals are amplified and the remainder of the signal lost, causing the signal to come through in an erratic manner.

To eliminate this undesirable feature, I have conceived the idea of biasing the first tube or tubes at a faster rate and to a greater extent than that of the subsequent tubes, accordingly

varying the characteristics of the related amplifier circuits. Since the grid swing on the first amplifier tubes, as caused by an incoming modulated wave, is so small, as compared with that produced by the amplified signal on the subsequent amplifier tubes, the grid bias on said first tubes may be shifted to practically any value, even beyond the cut-off point without introducing, to any noticeable extent, the distortion referred to above.

This is not so, however, with the other amplifiers, wherein the grid swing approaches comparatively high values. To prevent distortion occurring in these tubes, wherein the fairly large grid swing exists, such tubes should not be biased to the cut off point, and the volume-control grid-bias variations should not be of such value as to carry the grid bias beyond the cut-off value.

Accordingly, by an arrangement for biasing the first amplifier tubes at a faster rate than the subsequent amplifier tubes, sufficient control can be obtained without increasing the bias on the subsequent tubes to the cut-off point.

My invention, as briefly outlined above, possesses additional utility of a practical nature in that, in addition to its volume control functions, it might be utilized as a manually operated means whereby distortion of the type described above may be eliminated.

Accordingly, it is one object of my invention to provide a means whereby a uniform sound level in the output of a radio receiver may be maintained during periods of reception, at any predetermined value, over a wide range of signal variations, such as occur during fading or when tuning from one station to another.

Another object of my invention is to provide a means for volume control which will not introduce distortion on strong signals.

A further object of my invention is to accomplish the above effects in a manner which is entirely automatic.

An additional object of my invention is to provide means whereby distortion may be eliminated.

Additional features of my invention will be pointed out in the following description taken in conjunction with the drawings, which discloses a plurality of species of my invention, as applied to a receiver of the superheterodyne type, although it will be apparent that my invention is adaptable to receiving circuits of all types.

trates a simplified superheterodyne receiving circuit embodying one species of my invention.

Fig. 2 diagrammatically represents a modification of my invention in a similar circuit, only 5 the relevant portion of which is shown.

The system, as disclosed, comprises an antenna circuit 1, a radio frequency amplifier 2, a first detector stage 3, an intermediate frequency amplifier 5, a second detector 7, a stage of audio amplification 8, and a control tube 9 whereby automatic volume control may be obtained.

A source of potential 11 is provided for supplying the various thermionic devices of the system with desirable voltages, said source comprising 15 any of the well known means of obtaining a direct current potential, e. g.: a battery, direct current generator, rectifier and filter circuits or the like. An alternating current potential source, not specifically shown, is also provided for supplying current to the heaters 13, 15, 17, 19 and 21 20 and filament 23 of the tubes functioning in the circuit.

While the system disclosed is more or less conventional, a brief description of the same is considered advisable to enable the operation of my invention to be more clearly and readily understood.

Referring more particularly to Fig. 1; the antenna circuit is shown coupled to the input circuit 25 of the radio-frequency amplifier 2, the output of which is heterodyned in the 1st detector stage to an intermediate beat frequency which is accordingly amplified through the intermediate-frequency stage of amplification 5. The 2nd 30 detector 7 is provided for detecting the output of the intermediate-frequency amplifier 5, thereby reducing the intermediate frequency to an audio-frequency which is capable of being further amplified by the audio-frequency amplifier 8 provided for the purpose. Transformer coupling is used throughout the system but other means of interstage coupling, such as resistance or choke coupling, may be resorted to. While I have illustrated only one stage of radio frequency and 40 intermediate frequency amplification, it is obvious that a plurality of such stages may be used.

Although potentials of different values may be impressed on all the tubes, I have illustrated, for the sake of convenience and simplicity, similar voltages on the radio frequency and intermediate frequency tubes and, in like manner, the potentials on the 1st and 2nd detector are made similar. The cathodes of the radio frequency and intermediate frequency tubes are, consequently, shown connected in parallel arrangement to the point 27 on a voltage divider 29, the grids of the same tubes being connected, in a similar manner, through different lengths of a resistor 31, to the point 33 on the voltage divider 29, that portion of the divider between the points 27 and 33 45 providing a permanent bias on said tubes.

Similarly, a portion of the voltage divider between the points 35 and 37 provides grid-biasing potential for the 1st and 2nd detector tubes, for 50 it will be seen that connections from both points can be traced, by means of the conductor 39 and 41, to the cathodes 43 and 45 and the grids 47 and 49 of both of said tubes, respectively.

Plate potential for the radio frequency and intermediate frequency stages is obtained from a 55 common tap 51 on the voltage divider 29 and, in like manner, the detector tubes receive their plate potentials from a common point 33 on the divider.

70 Audio amplification is provided to comprise a

power tube 53 coupled to the output circuit of the 5 2nd detector through a step-up transformer 55; grid and plate potentials being supplied from points 33 and 57 on the voltage divider, suitable connections (not shown) being made to the filament coil (also not shown) to complete the grid and plate circuits of said tube.

For adjusting the loud-speaker volume to any 10 desired sound level and maintaining said level substantially uniform, a control tube 9 is provided. This tube is disclosed also as being of the heater type, but a filament type tube might be used in lieu thereof. A conductor 61, extending between the grid 49 of the detector tube and the grid 63 of the control tube, renders both grids 15 susceptible to the same signal influences. The low-tension side of the detector input circuit is connected to the potential source at the point 37 by a conductor 42. Negative-bias potential is provided for the control tube 9 by connecting a portion of the voltage divider between the cathode at point 37 and the grid of said tube at point 64 through a resistor 65. The filament 21 of the control tube 9 may be fed from the same source 20 as those of the other tubes.

25 The resistor 31 is also connected in the plate circuit of the control tube 9 between the plate and the source of potential. It will be obvious that any change in the current in said plate circuit will produce a corresponding change in the potential drop across said resistor. It is the drop across this resistor which is utilized in fulfilling the objects of my invention and provides a very simple expedient for obtaining the desired results, as will be more fully explained hereafter.

30 In the operation of the receiving apparatus disclosed in Fig. 1, the grid contact of the control tube 9 at the point 64 is adjusted to give a desired sound level at the loud speaker, and, as a result of my invention, this sound level will be 35 maintained substantially uniform, regardless of any variations in the strength of incoming signals. It will be noted that, in addition to the permanent bias on the radio and intermediate-frequency tubes, portions of the plate resistor 31 40 of the control tube 9 also constitute grid bias for the same tubes, more of the resistor being incorporated in the input circuit of the first tube than in that of the second. Consequently, the grid bias of the first tube will increase faster and 45 to a greater degree than that of the second tube.

50 Assuming an incoming signal to materially increase in strength, the grid of the control tube 9 will swing more positive, thereby causing an increase in current in the plate circuit of said tube, with a corresponding increase in the potential drop across the resistor. As a result, the grids of the radio-frequency amplifier tubes will swing more negative, and, because of the greater portion of the plate resistor being in the input 55 circuit of the first tube, the grid of the first tube will be made more negative than the grid of the second tube. Therefore, the conditions outlined above have been realized, and the distortion which would normally occur on strong signals 60 will have been eliminated.

65 In Fig. 2, I have disclosed alternative means of accomplishing results similar to those obtained by means of the species described in connection with Fig. 1. Only the relevant parts of the circuit are disclosed, the various elements of which bear the same reference numerals as in Fig. 1.

70 In the modifications disclosed therein, it will be noted that the grids of both amplifying tubes are connected to the same point on the plate 75

resistor 31, instead of at different points, as disclosed in Fig. 1. To obtain a relatively quicker and greater grid-bias swing on the grid of the first amplifier, I make use of a resistor in either the plate circuit or the cathode lead of the last amplifier; and I illustrate these alternative means by a switching arrangement which is adapted, in one position, to connect the resistor 61, in the plate circuit and, in the other position, to connect the resistor 69 in the cathode lead, as described. The effect of the resistor in the cathode lead is to reduce the negative bias on the grid of the last amplifier a substantial amount at the same time that the resistor 31 is functioning to increase the negative bias a greater amount, with the result that the grid receives an effective change due to the difference of the two. A sudden increase in signal strength, therefore, will cause the grid of the first amplifier to swing negative to a greater degree and at a quicker rate than that of the last amplifier, since the first grid receives the full effect of the resistor 31, whereas the last grid is only partially effected.

The effect of the resistor in the plate circuit is to increase the plate potential on the tube 5 as the bias on that tube is increased. This increase in plate potential will, therefore, function to reduce the effect produced by the increase in negative bias supplied by the automatic volume-control tube. Therefore, while the ultimate effect produced by the resistor in either the plate circuit or the cathode lead is the same, the manner in which the result is accomplished is different.

While I have disclosed my invention as embodied in a radio receiver of the type described, it is obvious that my improvements might be adapted to a receiving circuit of practically any type. A number of modifications of circuits are disclosed in my prior application referred to above, and the adaptation of my invention to any one of said circuits should be apparent. Accordingly, I do not wish to be limited to the specific embodiment of my invention described herein except insofar as is necessitated by the prior art and the appended claims.

I claim as my invention:—

1. In automatic volume control apparatus wherein two discrete potentials are employed to control amplifier gain, means whereby one of said discrete potentials is obtained by rectification of the amplifier output, and means whereby the second potential is derived from the cur-

rent flow in an impedance located in the circuit connecting the anode with the grid-to-cathode circuit of the amplifier.

2. The method of operation of an electrical wave amplifier so as to secure automatic gain control thereof, which comprises applying to said amplifier a gain control potential which varies automatically with the magnitude of the input of said amplifier and applying in the plate circuit only of said amplifier a second gain control potential which varies automatically as a function of said first gain control potential.

3. The method of operation of an electrical wave amplifier so as to secure automatic gain control thereof, which comprises applying to said amplifier a gain control potential which varies automatically with the magnitude of the input of said amplifier and applying to said amplifier a second gain control potential which varies automatically as a function of said first gain control potential, said second gain control potential being obtained by the voltage drop due to the flow of current in the anode circuit of said amplifier to the exclusion of the input circuit of said amplifier.

4. The method of operation of a carrier wave amplifier receiving electrical signals of varying magnitudes so as to secure an automatic control of the gain of said amplifier, which comprises impressing a direct current potential varying with signal strength upon the input circuit thereof and impressing upon the output circuit a second direct current potential automatically decreasing in magnitude as the strength of the received electric signals increases, both of said direct current potentials functioning as gain control voltages.

5. In an amplifier system, a plurality of amplifying stages in tandem and means for changing the amplifier characteristics of certain of said stages at a faster rate than those of subsequent amplifier stages in response to changes in carrier intensity whereby a uniform volume level for the system may be maintained without distortion.

6. In a system of the superheterodyne type having both radio frequency and intermediate frequency amplification stages, the method of maintaining a distortionless transmission level which comprises simultaneously varying the amplification of said radio frequency and intermediate frequency stages at different rates.

GEORGE L. BEERS.
